COMBINATION TYPEWRITER-CARD
PUNCHER

John P. Buckley, Washington, D. C.

Application December 3, 1935, Serial No. 52,733

16 Claims. (Cl. 164—113)

This invention relates to an improved recording mechanism and one object of the invention is to provide an apparatus of such construction that, when it is operated, a record card may have 5 perforations punched therein and a typewriter operated to type upon another card or sheet of paper a replica of the data represented by perforations in the card, and thus permit the operator to be sure that the card has been correctly 10 perforated.

While the apparatus is particularly adapted for use at the sending station of an apparatus such as disclosed in my copending application for a patent upon an improved automatic account- 15 ing and checking system filed November 14, 1934, Serial No. 752,909, now Patent 2,080,758, granted May 18, 1937, it is to be understood that it is not limited to this particular use and may be employed wherever found adaptable. Figs. 18, 19 20 and 20 of the patent just mentioned show a punching and printing device for which the modifications shown in the instant case may be substituted.

Another object of the invention is to so construct the apparatus that, when it is operated either by means of a rotary dial or through manipulation of the keys of a typewriter, a carriage carrying a card will be shifted longitudinally and transversely and thus brought into the proper position for accurately punching a record card carried by the carriage, or a punch will be shifted over a fixed card.

Another object of the invention is the provision of an apparatus of this character which 35 may be operated either through the medium of mechanical means or electrically energized means.

Another object of the invention is to provide an apparatus of this character which is simple 40 in construction, easy to operate and not only very accurate but also not liable to get out of order.

The invention is illustrated in the accompanying drawings wherein:

Fig. 1 is a front elevation view of one embodiment of the invention.

Fig. 2 is a view showing the apparatus partially in top plan and partially in section.

Fig. 3 is an end elevation looking from the right 50 in Figure 1 with portions omitted for the sake of clearness.

Fig. 4 is a fragmentary view of the dial and finger stop forming part of the apparatus.

Fig. 5 is a view in end elevation of a modified 55 embodiment of the invention.

Fig. 6 is a front elevation of the apparatus illustrated in Figure 5.

Fig. 7 is a fragmentary diagrammatic view of a modified form of key engaging shaft.

Fig. 8 is a perspective view of another modified 5 form of key engaging shaft and associated mechanism.

Fig. 9 is a diagrammatic view of another modified construction.

Fig. 10 is a view in cross section of a conven- 10 tional typewriter mechanism showing the es- sential parts thereof as used in the modification of Fig. 1.

This improved apparatus, when constructed as shown in Figs. 1 through 4, is provided with a 15 shaft 1, which extends longitudinally of a table 2, and at one end is mounted in the bearing at the upper end of a standard 3 where it is secured against longitudinal shifting movement by a pin 3' which engages in a similar groove found 20 in the shaft. This shaft extends through a casing 4 having a shaft receiving neck 5 at one side and at its opposite side a neck 6 terminat- 25 ing in a reduced end or bearing 7, snugly receiving the shaft with an end portion of the shaft 25 projecting from the bearing. The table 2 may be supported in any desired manner which will dispose the dial or finger ring 8 at the front of the casing within easy reach of a person operating the apparatus. A cylindrical shaft or sleeve 30 9 which is of less length than the shaft 1 fits snugly about the shaft and is held against rotation thereon by a key engaged in the key-way 1' formed in the shaft 1. The sleeve has one end portion formed with teeth, thus providing a rack 35 10, the teeth of which mesh with teeth of the gear 11 so that when the gear is rotated the sleeve will be shifted longitudinally upon the shaft 1. At its opposite end the sleeve carries a cam 12 which is fixed to the sleeve so that when the 40 sleeve is shifted longitudinally to dispose the cam over a predetermined one of the key levers 13 of a conventional typewriter mechanism or similar machine (for essential parts of which see Fig. 3 and Fig. 10) and the sleeve and shaft 1 then rotated, the cam will be swung into position to engage the selected key lever and swing it in an operative direction and thus cause a desired character to be imprinted upon a sheet of paper placed in the typewriter or equivalent machine in 45 50 the usual manner. By this arrangement the operator can type the desired data upon a sheet of paper A placed in the typewriter C around platen B against which type-bars 13' strike.

The gear 11 is fixedly mounted upon a shaft 14 55

journalized axially through the casing 4 with its outer or forward end projecting from the casing and carrying the finger ring 8 which is circular in shape and formed with a series of finger 5 receiving openings 15 disposed in front of numbers or other symbols (marked upon the top of the casing). By engaging a finger through a selected one of the openings 15 the finger ring may be turned until the finger engages the abutment fingers 16 and 16' carried by a shaft 17 which is rotatably mounted in bearings carried by a marginal portion of the casing as shown in Figure 4. This will prevent rotation of the dial or finger ring beyond the extent desired and the 10 cam 12 will be moved into position over the desired key lever. The shaft 17 is yieldably held against rotation in one direction by a spring 18 coiled about the shaft with one end anchored to the shaft and its other end secured to one of 15 the bearings in which the shaft is rotatably mounted. Rotation of the shaft by the spring is limited by engagement of the finger 16' and a stop 4' projecting from the casing 4. In order to limit rotation of the shaft 17 when the abutment fingers are moved there has been provided 20 an arm 19 which extends longitudinally of contacts 20 mounted in the casing. Engagement of the arm 19 with one of the contacts not only serves to limit turning of the shaft 17 and swing- 25 ing movement of the fingers carried thereby but also causes one of the contacts to be moved into engagement with the other and thus close an electric circuit through a magnet 21 constituting part of the apparatus.

Coincidentally with rotation of the shaft 14 a gear 22 fixed upon the rear end portion of the shaft will be turned and as this gear meshes with a rack bar 23 slidably mounted in bearings 24 carried by the casing 4 the rack bar will be slid longitudinally, the distance the rack bar travels being controlled by the extent to which the shaft 14 and gear 22 are turned. As the rack bar 23 moves longitudinally, the frame or carriage 25 carrying the card 26 which is slid into place under the flanges 27 of the frame will be shifted downwardly along the table 2 to an adjusted position in which the horizontal column having a number at its end corresponding to the number appearing above the type bar over which the cam 30 has been shifted will be disposed in position to have a perforation punched therein.

Movement of the frame or carriage to the adjusted position is accomplished as the operator's finger engages the abutment fingers 16 and 16' 55 and moves these fingers the limit of their movement. As rotation of the finger ring ends and the arm 19 engages the contacts 20 a circuit is closed to energize the magnet 21 and the armature 28 of the magnet will be drawn inwardly against action of the spring 29. A check valve 21' of a conventional form controls flow of air from the core of the magnet. As the armature is drawn inwardly the lever 30 which has one end connected to the armature and its other end pivoted to a mounting bar 31 carried by the magnet will be 60 swung towards the mounting bar into position to force the plunger 32 towards the card holding carriage and punch a perforation in the card. The spring 32' yieldably holds the plunger in an elevated position. The lever 30 not only operates the plunger 32 but also applies pressure to a plunger or rod 33 which is slidably mounted through the mounting bar and table 2 and yieldably held against depression by the spring 34. 65 In addition to imparting movement to the plunger

33 the lever also exerts pull upon the link 35 to pull upon the arm 35' and rotate the shaft 1 and the tubular shaft 8 and swing the cam 12 towards the key board so that the key lever over which the cam has been shifted will be moved in a direction to imprint a character upon the sheet of paper in the typewriter. As the plunger 33 is moved by the lever 30 the escapement pawl 36 will be rocked relative to the ratchet 37 and the shaft 38 which is journalized in the bearings 39 will be rotated. The pinion 40 fixed to the shaft 38 at the opposite end thereof from the ratchet 37 meshes with the rack 41 which is slidable longitudinally in the slot 42 formed in the table 2. This rack is provided at one end with a lug or finger 42' engaging an end of the card 26 in a manner to permit selective vertical movement of the card and frame and as the rack is moved, the card will be shifted in step by step movements to successively dispose the vertically extending columns of the card under the punch. This shifting of the card takes place before the card is perforated. It will thus be seen that perforations will be successively formed at selected points in the vertical columns of the card, and when completed the card will be ready for tabulation. While it has been stated that numerals are printed at ends of the horizontal columns of the card, letters of the alphabet or other symbols may be substituted. The spring 43 coiled about the shaft 38 and having one end anchored to the shaft and its other end anchored to the adjacent bearing 39 is tensioned as the rack bar 41 and the card are shifted to the starting position and rotates the shaft 38 to impart horizontal movement to the card as the escapement is actuated. As the operator removed his finger after turning the finger ring to a position in which further rotation of the finger ring is stopped by engagement of the operator's finger with the arms 16 and 16' the spring 44 coiled about the shaft 14 and tensioned during rotation of this shaft with the finger ring reverses rotation of the shaft and the gears or pinions 11 and 22 and the carriage and the tubular shaft will be returned to their initial positions. Another number can then be dialed and the operation will be repeated to form another perforation in the card, this perforation being formed in the vertical column next to the one in which the previous perforation was formed.

In order to send an electrical impulse to a distant station and cause energization of mechanism such as shown in my copending application, Ser. No. 752,909, filed Nov. 14, 1934 now Patent No. 2,080,758 granted May 18, 1937, there has been provided sending mechanism corresponding to the sending mechanism of the copending application. The mechanism about to be described is claimed in the patent referred to and hence is not claimed in the present case. This includes a shaft 45 journalized in the casing in spaced parallel relation to the shaft 14 and carrying a pinion 46 which meshes with a large gear or pinion 47 loose upon the shaft 14. This gear 47 has a ratchet 48 formed integral therewith which is engaged by a pawl 49. This pawl is carried by an arm 50 fixed to and extending radially from the shaft 14. Therefore during initial or forward rotation of the shaft 14 the pawl will slide over the ratchet but upon reverse rotation of the shaft as the finger ring returns to its original position rotary motion will be imparted to the ratchet and the gear 47 and through the pinion 46 to the shaft 45. A worm gear 51 carried by the shaft 45 and engaged by the worm

52 constitutes a transmission for the governor 53. The governor functions to prevent the shaft 45 from rotating too fast and during such rotation of this shaft a cam 54 mounted upon the 5 shaft moves into and out of engagement with one of the spaced contacts 55. These contacts are normally out of contact with each other and as the contact engaged by the cam is momentarily moved into engagement with the other contact a 10 circuit having the contacts incorporated therein will be closed and an electrical impulse pass through the circuit to energize apparatus controlled thereby. This apparatus may be an accumulator or any other apparatus desired.

15 When this device is in use the operator places a sheet of paper in the typewriter and a card in the carriage or frame 25. The dial is then operated by successively engaging a finger in openings through which the desired numerals 20 appear and the finger ring turned each time until the operator's finger engages the abutment arms 16 and 16' and is brought to a stop as the shaft 17 is turned and arm 18 moves the contacts 25 into engagement with each other to close the circuit through the magnet 21. During movement of a finger towards the abutment arms 16 and 16' the shaft 14 is rotated in a direction to shift the sleeve or hollow shaft 9 along the shaft 1 a sufficient distance to move the cam 12 into place over the key lever of the typewriter corresponding to the numeral dialed and at the same time the carriage will be shifted vertically by the gear 22 and rack bar 23 into position to dispose the horizontal column having the corresponding numeral at its end under the punch plunger 32. As the circuit of the magnet is closed as soon as the contacts 20 are moved into engagement with each other and this takes place practically simultaneously with engagement of 30 the operator's finger with the arms 16 and 16' and shifting of the carriage and hollow shaft to their adjusted positions, the lever 30 will be immediately moved towards the bar 34 and during this movement the hollow shaft 9 will be turned with 35 the shaft 1 to cause the cam to impart operative movement to the selected type bar through the key lever, the shaft 38 rotated to shift the card longitudinally to bring the first vertical column of the card under the plunger 32 and pressure then applied to the plunger to form a perforation in the card. The opening 2' formed in the table under the plunger permits unhampered movement of the plunger. Upon release of the finger ring the elements are restored to their 50 initial positions. The finger ring is then again operated to dial the next numeral desired and the operation repeated and a perforation formed in the second vertical column of the card, the card being moved horizontally in step by step movements to bring one vertical column after 55 another under the plunger from the initial position in which the card is initially disposed when applied to the carriage. After all of the numerals of a predetermined number have been dialed the card can be removed from the carriage and it will be found that the perforations in the vertical columns when read in accordance with numerals at ends of the horizontal columns in which they are formed will form the predetermined number.

60 The predetermined number will also have been typed upon the sheet of paper placed in the typewriter.

In the embodiment of the invention illustrated in figures 5 and 6 the apparatus is operated from 75 the key board of the conventional typewriter

mechanism C having platen B. When a selected key is depressed a rocker shaft 56 will be rotated. This rocker shaft is mounted in bearings 57 at opposite sides of the typewriter and has a single crank portion 58 which extends under all of the keys transversely thereof so that depression of any one of the key bars will cause rotation of the rocker shaft. As the rocker shaft turns, a cam 59 mounted upon one end thereof will move the contact 60 of the circuit maker and breaker 10 61 into engagement with the other contact thereof and a circuit closed through the magnet 62. As the magnet is energized the armature, which is in the form of a bar 63 having teeth 64 on one side serving as a rack bar, is retracted. The rack 15 teeth 64 mesh with a gear or pinion 68 carried by the shaft 69 upon which the bevelled gear 70 is loosely mounted and yieldably coupled to the shaft by a spring 71 having its ends fixed to the gear and shaft. As the gear 70 meshes with the 20 bevelled gear 72 carrying a pinion 73, and the pinion meshes with the rack bar 74 of the shaft 75, the shaft will be slid longitudinally through the bearings 76 in which it is mounted until the abutment lug 77 carried by the shaft engages the 25 depending arm or tongue 13' of the depressed key of the typewriter and further movement of the shaft stopped. It will thus be seen that rotation of the shaft 72' carrying the gear 72 and pinion 73 and rotatably carried by a bracket 78 will be 30 controlled and as this shaft also carries a small pinion 79 meshing with teeth of the rack bar 80 extending from the card holding carriage 81, the carriage will be shifted only a sufficient distance to move a predetermined horizontal column of 35 the card 82 into position to be punched. The gear 79 ceases to rotate as soon as the lug 77 engages the tongue of the depressed key but the shaft 69 and pinion 68 may continue rotating and therefore movement of the armature 63 will not be stopped but may continue a sufficient distance for the lug 83 of the armature to engage the free end of the pivotally mounted lever 84 and swing the lever into position to actuate the punching plunger 85 and the stem 86 of the escapement 40 45 87. This escapement corresponds to that shown in Figure 3 and when actuated permits intermittent rotation of the shaft 88 carrying a pinion 89 which meshes with a rack bar 90 corresponding to the rack bar 38 and serving to impart step by step horizontal movement to the card. This portion of the apparatus is similar to that shown in Figures 1, 2 and 3 and previously described. When the operator removes his finger from the depressed key the spring 91 returns the rocker 50 55 shaft 58 to a raised position and the contacts of the circuit maker 61 separate. The spring 71 then uncoils to rotate the shaft 69 and withdraw the armature and as the lug 83 moves out of engagement with the lever 84 rotation of the gears 60 70 and 72 and the pinions 73 and 79 act upon the rack bars 74 and 80 to restore the shaft 75 and the card frame or carriage to their initial positions. The card will, however, have been shifted horizontally to move the second vertical column 65 to a position under the punch.

Instead of depending upon electricity to operate the apparatus it may be hand-operated in which case the selected type key will be depressed with a finger of one hand and held depressed while 70 a finger of the other hand is applied to the button or head 92 at the outer end of the armature or rack bar 63 and pressure applied to force the same into the magnet. During this movement the shaft 75 will first be shifted longitudinally 75

until the lug engages the tongue of the depressed key and further pressure will cause the lug 83 to move the lever 84 into position to engage the stem 86 to actuate the escapement 87 for horizontal adjustment of the card carriage and then operate the plunger 85 to perforate the card. The rack bar 63 and the depressed key are then released and return movement of the parts takes place.

10 Instead of using a rock shaft 56 having a single crank portion 58 the rock shaft 93 shown in Figure 7 may be used. This rock shaft is rotatably mounted at its ends in bearings 94 and has intermediate portions bent to form cranks 95 disposed under cooperating key bars 13. A finger 95' formed on each crank 95 serves to engage a side face of the companion key 13 and absorb shock when the key is struck by the lug of the sliding shaft 75. In Figure 8 a rock shaft 96 having a single elongated crank portion 97 is used and yieldably held against rotation in one direction by a spring 98. This construction is primarily intended for a hand-operated apparatus and the bridge of the crank is disposed in front of the vertically extending portions 99 of the keys 13. A notch 100 is formed in the vertical portion of each key and when a key is depressed the bridge of the crank 97 enters the notch formed in the depressed key and maintains the rock shaft in an adjusted position. The depressed key is secured in the depressed position by engagement of the crank in the notch of the key and as soon as the arm 102 engages the arm 101 to rock the shaft 96 and move the crank out of the notch the key 35 will be released and return to a raised position.

In the modified construction illustrated in Figure 9 sliding of the hollow shaft 103 which takes the place of the shaft 75 and is supported upon the shaft 104 is controlled by a plurality of magnets 105 mounted at opposite sides of the shaft 103. The rack teeth 103' of the shaft 103 mesh with the pinion 78. The armatures 106 of the magnets are yieldably held retracted by springs 107 but when a predetermined magnet is energized its armature will be shifted to an extended position in which it projects into position to engage an abutment 108 of the hollow shaft 103 and limit sliding movement of the shaft. The wires 109 leading from coils of the magnets are attached to individual terminals 110 each of which is yieldably supported by a spring 111 and has its stem 112 slidably mounted through an insulating bar 113. Wires 114 lead from opposite ends of the coils of the magnets to one end of the coil 55 of the magnet 105, which corresponds to the magnet 82, the other end of the coil of this magnet being connected by a wire 116 to one side of the battery 111. The switch 117 is interposed in the wire 118 leading from the other side of the battery, which wire has branches grounded to certain keys 13 of the typewriter and it will be readily seen that when one of these keys is depressed it will engage a cooperating terminal 110 and close a circuit through a predetermined magnet 105 as it moves downwardly. Therefore the selected magnet 105 and the magnet 115 will be energized and the apparatus set in operation, sliding of the hollow shaft being stopped when the abutment 108 carried thereby engages the projected armature of the energized magnet 105. When the key is released and moves upwardly to its normal position the circuit through the energized magnets will be broken and the apparatus will be restored to its initial condition. The switch 117 will permit disconnection when it is

desired to use the typewriter for writing without punching.

Having thus described the invention, what is claimed is:

1. In an apparatus of the character described, a 5 shiftable carriage adapted to hold a record card, a key board, a rock shaft having a crank portion under the key board, a rack bar extending from said carriage, a shaft slidably mounted for movement transversely of the key board, a rack 10 carried by said shaft, pinions meshing with the racks of the carriage and shaft, means for simultaneously imparting rotation to said pinions to shift the shaft transversely of the key board and to shift the carriage to an adjusted position, 15 means carried by said shaft for engaging a depressed key to limit shifting of the shaft and consequently limit shifting of the carriage beyond a position determined by the depressed key, means to actuate the means for rotating the pinions having controlling means actuated by rotation of the crank shaft, and means for perforating a card in said carriage actuated by the means for rotating the pinions.

2. The structure of claim 1 wherein the means 25 for imparting rotation to the pinions includes an electro-magnet having a circuit including a circuit maker disposed adjacent the rock shaft, and a cam carried by the rock shaft and moved therewith to close the circuit maker when the rock 30 shaft is rotated by engagement of a depressed key with the crank of the rock shaft.

3. In an apparatus of the character described, a shiftable carriage adapted to hold a card, perforating means overlying the carriage, a key 35 board, a rock shaft having a crank portion extending under the key board transversely thereof to impart rotation to the shaft when a selected key is depressed and engages the crank, a rack carried by said carriage, a rack bar having 40 a portion thereof extending under the key board transversely thereof, a gear and a pair of pinions turning as a unit, said pinions meshing with the rack bar and the rack of the carriage, an abutment carried by the rack bar for engaging a 45 depressed key to limit sliding of the rack bar and consequently limit shifting of the carriage beyond a position disposing a predetermined portion of a card under the perforating means, said position depending upon the selected key whereby a 50 perforation will be formed in the predetermined portion of the card carried by the carriage, and means responsive to rotation of the rock shaft to impart rotation to the pinions through the medium of said gear and after shifting of the 55 carriage actuate the perforating means.

4. The structure of claim 3 wherein the means for actuating the perforating means and imparting rotation to the pinions includes a plunger, an electro-magnet, the plunger constituting the 60 armature of the electro-magnet, and a circuit for the electro-magnet having incorporated therein a circuit maker normally open and adapted to be closed when the rock shaft is rotated by engagement of a depressed key with its 65 crank.

5. The structure of claim 3 wherein the means for actuating the perforating means and imparting rotation to the pinions includes a plunger formed with a rack, a pinion meshing with the 70 rack of said plunger, a shaft carrying the pinion and rotatably mounted, a gear loose upon the shaft and meshing with the gear turning with the pair of pinions, a spring coiled about the shaft with one end anchored to the shaft and its 75

other end anchored to the gear loose upon the shaft, and an abutment carried by said plunger for engaging and actuating the perforating means during sliding of the plunger subsequent to shifting of the carriage.

6. In an apparatus of the character described, a shiftable carriage adapted to hold a card, perforating means overlying the carriage and having an operating lever, a shank for said carriage provided with a longitudinally extending rack, and actuating means for the lever and the carriage including a plunger extending transversely of said shank and said lever and provided with a longitudinally extending rack, means for reciprocating said plunger, an abutment carried by said plunger for engaging the lever and effecting operation of the punch when the plunger is moved longitudinally in one direction, a gear and a pinion turning as a unit with the pinion meshing with the rack of said shank, a pinion meshing with the rack of said plunger, a shaft carrying said pinion and rotatably mounted, a gear loose upon said shaft and meshing with the first gear, and a spring coiled about said shaft with its ends anchored to the shaft and the gear loose upon the shank, and means associated with loosely mounted gear for selectively limiting the degree of rotation thereof.

7. In a card punching machine, a punching mechanism, means providing relative step up movement between a card and the punching mechanism and means providing selective relative movement between the card and punching mechanism at right angles to the step-up movement, manually operable means for accomplishing selection of the last named relative movement, means actuated by said last named means for automatically operating the punching mechanism after each selection made and means automatically operated by said punching mechanism to operate said step up means after each operation of the punching mechanism.

8. In a device for printing selected indicia and substantially simultaneously effecting correlated card punching, a series of type actuating elements, means for advancing a card in one direction, a punching device, said card and said punching device being relatively movable with respect to each other laterally of the first direction; means for selecting the relative lateral position of the card and punching device including means for operating the corresponding type actuating element, the punching device, and the card advancing means.

9. In a card punching mechanism, a punching device, a card holder adapted to carry a card adjacent said punching device, said card having a series of longitudinally extending columns transversely arranged, said card holder being mounted for transverse movement relative to said punching device and said card holder having means to guide the card longitudinally of said punching device, means associated with said card holder for determining its lateral position relative to said punching device means included with said last named means for automatically actuating the punching device and means actuated by said punching device for automatically changing the longitudinal position of the card in the guide means after each punching operation.

10. In a device for printing selected indicia and substantially simultaneously effecting correlated card punching, a printing mechanism having a series of type actuating elements, a punching mechanism, means for advancing a

card in one direction relative to the punching mechanism, means for selectively positioning said card and said punching mechanism relative to each other at any one of a given number of points on a line at right angles to the direction of advancement, and means for making successive selections including means for automatically operating correlated type elements, the punching mechanism and the card advancing means as each selection is made.

11. In a device for perforating record forms, a punching mechanism, means for advancing the record form in a given direction relative to the punching mechanism, means for effecting relative movement between the record form and the punching mechanism at right angles to the given direction; means, comprising a group of keys and electro-mechanical means associated with said keys, for selectively controlling the degree of the last named movement said last named means further including means for automatically operating the punching mechanism and the advancing means.

12. In a device for perforating record forms, a punching mechanism, means for advancing the record form in a given direction relative to the punching mechanism, selectively operable means for effecting relative movement between the record form and the punching mechanism at right angles to the given direction, means operable by the last named means for operating the punching mechanism and mechanical means actuated by the punching mechanism for operating the advancing means.

13. In a card punching machine, a punching mechanism, means providing relative step-up movement between a card and the punching mechanism and electro-mechanical means arranged to cause relative movement between the card and punching mechanism at right angles to the step-up movement, manually operable means for initiating and determining the degree of the last named relative movement, means actuated by said electro-mechanical means for automatically operating the punching mechanism after each operation of said manually operable means and means operable by said punching mechanism after each operation thereof for operating said step-up means.

14. In a device for perforating record forms, a punching mechanism, means for advancing the record form in a given direction relative to the punching mechanism, electro-mechanical means having a predetermined operating range for effecting relative movement between the record form and the punching mechanism at right angles to the given direction, said electro-mechanical means including a resilient drive permitting selective limitation of said last named relative movement to various points within the operating range thereof, positive drive means associated with said electro-mechanical means constructed and arranged to operate the punching mechanism as the electro-mechanical means approaches an extremity of its operating range, means operably associated with the punching means for operating the advancing means, and means for energizing said electro-mechanical means and selectively limiting said second named relative movement between the record form and the punching mechanism.

15. In a device for perforating record forms, a punching mechanism, means for advancing the record form in a given direction relative to the punching mechanism, electro-mechanical means

- for effecting relative movement between the record form and the punching mechanism at right angles to the given direction, means for energizing said electro-mechanical means including means
- 5 for selectively controlling said last named movement, means operable by the electro-mechanical means for operating the punching mechanism and means operably associated with the punching mechanism for operating the advancing means.
- 10 16. In a device for printing selected indicia and substantially simultaneously effecting correlated card punching, in combination a series of type actuating elements, means for advancing a card in one direction, a punching device, said card and

said punching device being relatively movable with respect to each other laterally of the first direction, operating means relatively positionable with respect to said type actuating elements and operably associated with said punching device; 5 mechanical means for selecting the relative lateral position of the card and punching device, for a given punching operation, including means for simultaneously positioning the operating means with respect to the corresponding type actuating 10 elements and means operably associated with said mechanical means for operating said punching device.

JOHN P. BUCKLEY.
